UNITED STATES PATENT OFFICE.

HOMER G. KELLOGG, OF DETROIT, MICHIGAN, ASSIGNOR TO MOTOR PRODUCTS CORPORATION, OF DETROIT, MICHIGAN, A CORPORATION OF NEW YORK.

HINGE.

Application filed February 28, 1927. Serial No. 171,474.

The present invention relates to hinges and more particularly to sheet metal hinges wherein the leaves themselves of the hinge are formed to provide means taking the place 5 and function of the usual pintle.

Among the objects of the present invention is a hinge of the type indicated which is fixed against relative longitudinal movement of the leaves and yet free to carry out the 10 hinge function.

Another object is a hinge of the type indicated which may be mounted in a vertical, or substantially so, position and support considerable load.

15 Other objects will readily appear to those skilled in the art upon reference to the following description and accompanying drawing in which:

Fig. 1 is a cross section of a hinge connecting for example, a door to its frame;

Fig. 2 is an elevation of the hinge;

Fig. 3 is a section of the hinge on line 3—3 of Fig. 2 but on an enlarged scale;

Fig. 4 is a section similar to that of Fig. 25 3 but showing an intermediate stage of the manufacture of the hinge.

As indicated in the drawing the hinge for the most part is similar in form and action to the hinge described and claimed in copending application Ser. No. 96,645, filed March 30 22, 1926 by the present inventor, and comprises two leaf portions 10 and 11 each being a metal strip of a length equal to the length of the hinge and each secured to the parts to 35 be hinged in any suitable manner as by screws 13, if screws may be used, or welded, if metal to metal contact, or in any other suitable fashion.

The two parts or leaves 10 and 11 are provided with longitudinal beads 20 and 21 which are each substantially semicircular in section with the outer edges 22 and 23 turned inwardly, the edge 22 substantially radially of the bead and the edge 23 parallel 45 with edge 22. The two arcs are such that when the hinge is in closed position, the one embraces the other as indicated in Figs. 1 and 3 and in such position these arcs can be considered as described from a common center 50, which center is located a short distance from the edge 25 of the inturned portion 22 of bead 21. The bead 21 takes the place of and functions as the pintle of the hinge.

It will be noted that the edge 24 of the in-

turned portion 23 extends beyond the edge 55 25 of part 22 and that there is a groove 26 along the former edge. This groove 26 will be approximately arc-shaped in section and is described from the same center 50 as portions 20 and 21, having a radius equal to the 60 distance from this center point 50 to one corner 27 of the edge 25.

In the prior application, the hinge is the same as the present one as so far described, but in the prior hinge the two parts are fully formed and assembled together by sliding the one longitudinally into the other, no provision being made for vertical mounting or the carrying of any load tending to move the leaves relatively longitudinally.

70 In the present hinge, the leaf 11, the inner one, is formed as in the prior hinge and is then provided with one or more rectangular notches 30 (only one being shown). The leaf 10 is then formed but the inturned end 23 75 not set at the final position, that is, it is turned to about the position indicated in Fig. 4 so that when the parts 10 and 11 are slid together edge 23 will be spaced from edge 22.

When the two parts have been formed as 80 indicated, they are slid together as in the prior hinge but in each of the notches 30 is placed a pin 31 of the form shown in Fig. 2. This pin consists of a short piece of hardened steel rod having flat ends and with circumferential grooves forming a plurality of angular edges 32. And when thus assembled, the whole is placed in a suitable grooved die or anvil with part 20 in the groove, and struck with a suitable lined tool or mating 90 die upon edge 23 to force the latter to the position shown in Fig. 3, its finished position.

This causes the edges 32 of pin 31 to be embedded in the metal of the bead 20 of leaf 10 at several points, for example, at 60, 61 95 and 62, as indicated in Fig. 3 and with the abutment of the pin ends against the ends of notches 30 provides a positive and permanent lock against relative longitudinal displacement of the leaves.

100 The number of pins 31 and their distance apart will depend largely upon the service required of the hinge, usually, however, they will be spaced a few inches apart and the number determined by the length of the hinge. And the diameter of the pins should be large enough to cause the edges 32 to enter the metal of the outer bead but not so large

that the notches 30, in order to accommodate the pins, will have to be deep enough to be exposed when the hinge is closed.

Having now described the invention and the preferred form of embodiment thereof it is to be noted that the said invention is to be limited not to the specific details herein set forth and illustrated but only by the scope of the claims which follow.

10 I claim:—

1. In a sheet metal hinge in which the leaves are provided with beads of which one embraces the other, a pin provided with a plurality of projecting portions embedded in

the inner surface of the outer bead and lying 15 in slots in the inner bead with its ends abutting the ends of the slots, whereby the leaves are prevented from relative longitudinal movement.

2. In a sheet metal hinge in which the 20 leaves are provided with beads of which one embraces the other and which are separable only by relative longitudinal movement, means for preventing such movement, said means consisting of a member fixed in the 25 outer bead and abutting shoulders on the inner bead.

HOMER G. KELLOGG.
